UNITED STATES PATENT OFFICE.

FRANK WILLETT WALTON, OF EAST ORANGE, NEW JERSEY, ASSIGNOR TO WESTINGHOUSE LAMP COMPANY, A CORPORATION OF PENNSYLVANIA.

BASE FOR THEFTPROOF LAMPS.

Application filed April 10, 1925. Serial No. 22,005.

This invention relates to bases for incandescent electric lamps, screw plug connectors and similar articles adapted to be received in screw sockets and more particularly to the provision in articles of this nature of means for preventing unauthorized removal thereof from their sockets.

Considerable expense and inconvenience has been experienced in the past in the frequent removal of incandescent electric lamps from their sockets in public places, shops, factories, warehouses, etc., and while numerous attempts have been made heretofore, to provide satisfactory means for locking lamps and similar screw threaded objects into their sockets, such attempts have either involved the use of specially constructed sockets, usually provided with locking means requiring a special key to insert and remove a lamp therefrom or in complicated and expensive base construction.

One of the objects of the present invention is to provide a base for an incandescent electric lamp which is simple in construction, inexpensive to manufacture and which may be used with the ordinary lamp sockets without special keys, etc. and which will be effective to prevent unauthorized removal of the lamp therefrom.

Another object is to provide a base for an incandescent lamp formed in a plurality of parts which may be readily screwed into the ordinary standard lamp socket as a unit but which cannot be removed therefrom without causing a separation of said parts and thereby rendering the lamp inoperative.

Another object is to provide a lamp which when inserted into a lamp socket, cannot be removed therefrom without rendering the same inoperative but which does not necessitate for its removal breakage of the glass parts thereof.

Another object is to provide an improved base and socket for an incandescent lamp, screw plug or similar object which may be effectively locked together by the mere act of screwing the article into the socket and which cannot thereafter be removed without separation of the base into independent parts and consequent rupture of a current conductor.

Other objects and advantages will hereinafter appear.

While the invention will be described in connection with a base for an incandescent

lamp, it is to be understood that it is equally applicable to screw plug connectors and similar articles adapted to be threaded into sockets or other receptacles.

In accordance with this invention, the screw shell which may constitute the base for an incandescent lamp or one of the contacts of a screw plug connector or similar object, is formed in two parts normally retained in proper relation to each other by means of a resilient connector contained therein. One half of the threaded shell carries the central contact to which one of the leading-in wires of the lamp is joined and the other half of the shell is cemented to the lamp bulb and has the other leading-in wire connected thereto. The base is so constructed that in screwing the lamp into the socket, the two parts thereof will be held together so as to be inserted into the socket as a unit but should an attempt be made to remove the lamp from its socket, the outer portion of the base, that is, that portion carrying the central contact, will be restrained from rotation within the socket and the portion of the base to which the lamp is cemented will be screwed outwardly away therefrom causing a separation of the two parts and resulting in the breakage of the leading-in wire connected respectively to the central contact and to the bulb.

After the bulb and the portion of the base secured thereto have been removed from the socket, access may be had to the interior of the other half of the base to release the means by which it is locked in the socket and the remaining portion of the base may then be readily screwed out of the socket. In order to insure that the outer half of the base will not screw out of the socket with the bulb, the socket may be provided with slots or depressions to receive a projection on the outer end of the base.

The invention may be more fully understood by reference to the accompanying drawings in which,

Fig. 1 is an elevation of an incandescent lamp having a base constructed in accordance with this invention;

Fig. 2 is a drop perspective of the base; 105
Fig. 3 is a section of line III—III of Fig. 4; and,

Fig. 4 is a sectional view of a lamp socket with a lamp partially removed therefrom. The lamp shown in Fig. 1 comprises a 110

bulb 1 having a base 2 attached thereto and formed in two separate pieces 3 and 4. The outer portion 3 of the base carries the central contact 5 of the lamp which is connected to one end of the filament by means of the leading-in wire 6. The other half 4 of the base is cemented to the bulb as at 7 as is well known in the art. The outer portion of the shell 3 is retained normally in proper relation with respect to the inner portion 4 thereof by means of a flat spring 8 which is contained within the base and has on one end thereof, a pair of outwardly extending prongs 9 and 10 adapted to be received in perforations 11 and 12 formed in the two halves 3 and 4, respectively, of the base.

When the lamp is screwed into the socket, the outer portion 3 of the base will be locked therein, as will presently appear, and when an attempt is made to remove the lamp, the inner portion 4 of the base will be screwed outwardly away from the central contact 5, causing rupture of the leading-in wire 6.

The spring 8 is so positioned within the two halves of the base that the prongs 9 and 10 extending through the perforations in the base, project outwardly therefrom and are inclined in a direction oppositely to the direction of rotation of the base when it is threaded into the socket so that they will not hinder the insertion of the lamp therein. The adjacent edges of the two halves of the base are provided with cooperating clutch members 13 which normally engage to permit the base to be rotated as a unit into the socket but which permit relative rotation between the two halves of the base in the opposite direction. When the lamp is screwed into the socket, the projecting ends 9 and 10 of the spring are pressed inwardly into the openings 11 and 12, by the inner wall of the socket and through the combined action of the spring 8 and the clutch member 13, the two halves of the base are screwed as a unit into the socket.

However, should an attempt be made to unscrew the lamp from the socket, the sharpened edge of the projection 9 of the spring will dig into the wall thereof and prevent the outer half 3 of the base from being further rotated. The inner half 4 of the base, however, may be readily turned with the bulb, the edge of the opening 12 in the shell sliding over the end of the projection 10, which is inclined in the direction of rotation thereof and therefore forms no appreciable obstacle to the removal of this half of the base. As the bulb and the lower half of the base move outwardly, tension is put upon the leading-in wire 6 to cause the same to be broken and the lamp rendered useless.

It should be noted that in removing a

lamp, it is unnecessary to break the glass portions thereof, but the entire bulb and a portion of the base are removed together. After they have been removed, access may be readily had to the spring 8, and by a slight rotation thereof, the projection 9 may be withdrawn through the opening 12 into the interior of the base and out of contact with the wall of the socket. The two halves of the base are not distorted or otherwise injured in the removal of the lamp from the socket and may be salvaged, reunited and again used.

In order to insure that the outer half 3 of the base will not be removed from the socket with the bulb, the socket may be provided with a depression or opening 14 into which the projecting end 9 of the spring will enter and positively hold the outer portion of the base from further rotation.

While but a single embodiment of the invention has been described herein, it is to be understood, of course, that this invention is susceptible to many variations and that modifications and changes may be made therein without departing therefrom.

What is claimed is:

1. A base for an incandescent lamp comprising a threaded shell composed of two parts adapted to be screwed into a lamp socket in unison when rotated in one direction and dividable when rotated in another direction for removal.

2. A base for an incandescent lamp comprising a threaded shell composed of two parts, means connecting said parts adapted to permit the shell parts to be screwed in one direction into a socket in unison, said means operating to cause a division of the shell when screwed in an opposite direction to prevent the unitary removal of said parts from a socket.

3. A base for an incandescent lamp comprising a threaded shell composed of two parts, a spring connecting said parts adapted to permit the same to be screwed into a lamp socket in unison but serving to cause a separation of the shell parts when screwed in an opposite direction in an attempt to remove said parts from the socket.

4. A base for an incandescent lamp comprising a threaded shell composed of two parts, disposed in axial alignment and having adjacent clutch faces whereby the two parts may be rotated in unison in one direction and independently in the opposite direction.

5. A base for an incandescent lamp comprising a threaded shell composed of two parts disposed in axial alignment, means cooperating with said shell parts to permit the lamp to be screwed into a socket with said parts in fixed relation and means to prevent the unitary removal of said shell parts.

6. A base for an incandescent lamp com-

prising a threaded shell composed of two parts disposed in axial alignment and having adjacent clutch faces whereby the two parts may be rotated in unison in one direction and independently in the opposite direction and means joining said parts and maintaining them normally so positioned as to permit the lamp to be screwed into its socket said means operating to render the lamp ⁵ operative upon an attempt to remove the same from the socket.

7. A base for an incandescent lamp comprising a threaded shell composed of two parts, each having a perforation therein and ¹⁵ a resilient member within said base engaging with said perforations to normally maintain said parts in proper relation but allowing relative movement therebetween.

8. A base for an incandescent lamp comprising a threaded shell composed of two parts, each having a perforation therein and a resilient member within said base engaging with said perforations to normally maintain ²⁰ said parts in proper relation but allowing relative movement therebetween in one direction only.

9. A base for an incandescent lamp comprising a threaded shell composed of two parts, each having a perforation therein and ²⁵ a resilient member within said base engaging with said perforations to normally maintain said parts in proper relation to permit the lamp to be inserted in its socket but allowing relative movement therebetween so as to render the lamp inoperative when an attempt ³⁰ is made to remove the lamp from its socket.

10. An electrical connector adapted to be inserted into a threaded socket, comprising a composite threaded shell, an insulated contact member on one part of said shell and ⁴⁰ means for permitting the shell to be inserted into a socket as a unit upon rotation in one direction, said means operating upon an opposite rotation of said shell to cause a relative movement between the component parts ⁴⁵ thereof to render the connector inoperative.

11. A base for an incandescent lamp com-

prising a composite threaded shell, a connector within said shell engaging both of ⁵⁰ said sections thereof to normally retain them in proper relation, said connector having means extending through one of said sections adapted to lock the same in a socket.

12. A base for an incandescent lamp comprising a threaded shell divided transversely ⁵⁵ into two sections, a resilient connector within said shell engaging both of said sections to normally retain them in proper relation, said connector having a sharpened prong extending through one of said sections adapted to engage the wall of a socket to lock the same therein.

13. A base for an incandescent lamp comprising a threaded shell divided transversely ⁶⁰ into a plurality of sections, a connector within said shell engaging said sections to normally retain them in proper relation, said connector having a projection extending through an opening in one of said sections adapted to engage the wall of a socket to ⁶⁵ lock the same therein.

14. A base for an incandescent lamp comprising a threaded shell divided transversely ⁷⁰ into two sections, a resilient connector encircling the inner wall of said shell engaging both of said sections to normally retain them in proper relation, said connector having means extending through one of said sections adapted to lock the same in a socket.

15. A base for an incandescent lamp comprising a threaded shell formed in two longitudinal sections, a resilient connector encircling the inner wall of said shell engaging ⁷⁵ both of said sections to normally retain them in proper relation, said connector having a projection extending through one of said sections adapted to engage a socket to lock the same therein, said connector permitting removal of the other of said sections from ⁸⁰ the socket.

In testimony whereof, I have hereunto ⁹⁰ subscribed my name this 9th day of April, 1925.

FRANK WILLETT WALTON.
